UNITED STATES PATENT OFFICE.

EBERHARD FABER, OF NEW YORK, N. Y.

ERASER.

No. 840,485.

Specification of Letters Patent.

Patented Jan. 8, 1907.

Application filed September 29, 1906. Serial No. 336,778.

To all whom it may concern:

Be it known that I, EBERHARD FABER, a citizen of the United States, residing in the city of New York, in the county and State of New York, have invented a certain new and useful Improvement in Erasers, of which the following is a specification.

This invention concerns erasers, and has reference more particularly to erasers for removing type-written matter, and which consist of a disk of rubber mounted for rotation between two sheet-metal plates. Preferably, though not necessarily, the plates may be extended beyond the periphery of the rubber disk, and have secured between them a bundle of bristles, by which the particles removed from the sheet can be brushed away.

The object of the invention is to effect certain improvements in the construction of erasers of this type, the improvements being directed at lengthening the period of usefulness of the eraser without increasing its cost. These features, which I believe to be characteristic of my invention, will be more fully set forth in the following description, which is to be taken in connection with the accompanying drawings.

In the drawings, Figure 1 is an elevation of the eraser. Fig. 2 is a central section thereof on line 2 2 of Fig. 1, and Fig. 3 is a section on line 3 3 of Fig. 2.

Referring to the drawings, A indicates a disk of rubber specially prepared for the erasure of type-written matter. B B' indicate two sheet-metal plates lying one on either side of the disk A, and in the ends of which openings are formed to receive an eyelet C, which extends through these openings and also through a central opening in the disk A. The ends of the eyelet are turned over, so as to hold the parts firmly together but permit rotation of the disk A thereon. The plates B B' are extended on one side of the eyelet C beyond the periphery of the disk A, and a bundle of bristles D is secured between them in the manner hereinafter described. The ends of the plates B B', between which the disk A is secured, are each so shaped as to provide two portions, one extending a greater distance from the pivotal axis of the disk than the other. The greater portion of each plate may include the part of the plate extending beyond the periphery of the disk to hold the bristles when a brush is provided and preferably extends about one hundred and eighty degrees around the piv-

otal axis of the disk—that is, it includes substantially all that portion lying below the horizontal diameter of the disk in Fig. 1. This portion, except as to the extension for holding the bristles, preferably extends about one-half the distance from the center to the periphery of the disk.

The remaining or lesser portion of the end of each of the plates B B' is cut away, so as to overlie a much smaller part of the disk A. For this reason the portions of the ends of the plates B B' which extend the greater distance from the center serve to stiffen the parts of the disk A adjacent thereto, so that when the eraser is new the part thereof adjacent to these larger portions may be used, and in doing so the disk will not flex to such extent as to render the operation of erasing slow and difficult. However, when the eraser has been used and worn away so much that the periphery of the disk lies close to the periphery of these larger portions the part adjacent to the portion of the ends of the plates which extends a less distance from the center can then be used. If this portion of the ends of plates B B' were formed on an unbroken curve, the flexure of the disk A when the eraser is being used would press the disk against this curved edge with such force as to cut into it. In accordance with my invention I avoid this cutting of the disk by scalloping the ends of the plates, so as to provide a series of discrete projections thereon. In this way the flexure of the rubber brings it into engagement with a series of curved edges, each separated from adjacent ones by substantial spaces, and if the edges of these curved projections should cut into the rubber the parts thereof lying between the curved projections and which would not be cut would hold the peripheral portion of the disk to the central portion and permit of using the eraser until it was worn down flush with the edge of the plates.

In securing the bundle of bristles D between the outer ends of the plates B B', I provide a sheet-metal band d, wrapped tightly around the inner ends of the bristles, so as to hold them firmly, and this end of the bristles with the band thereon is then inserted between the outer ends of the plates B B'. A rivet d' is then passed through openings in the plates and the band d and through the bundle of bristles and its ends turned over so as to unite the parts firmly. In preparing the plates B B' the outer ends thereof are

- serrated and the serrations turned inwardly, somewhat as shown. By this construction the bundles of bristles, each held together by its band *d*, may be prepared in a preliminary 5 operation, and the pressure of the band on the bristles at one end thereof causes the other end to spread, as illustrated in the drawings. Also the single rivet shown serves to hold the parts firmly together, and when 10 the ends of the plates *B* *B'* are drawn together by this rivet the inwardly-turned serrations on the ends of the plates are carried in among the bristles and assist in spreading them at their free ends.
- 15 Having now described my invention, what I claim as new therein, and desire to secure by Letters Patent, is as follows:
1. An eraser having a pair of metallic plates, and a disk of rubber pivotally mounted 20 between said plates, a portion of said plates about the pivotal axis of said disk extending a less distance from said axis than the remaining portion and said portion ex-

tending the less distance from the axis being provided with discrete projections, substantially as set forth. 25

2. An eraser having a pair of metallic plates, a disk of rubber pivotally mounted between said plates adjacent to one end thereof, and a bundle of bristles secured between 30 said plates at the other end thereof and beyond the periphery of the disk, the ends of said plates between which the disk is supported having a portion about the pivotal axis of the disk extending a less distance 35 from said axis than the remaining portion and said portion extending the less distance from the axis being provided with discrete projections, substantially as set forth.

This specification signed and witnessed 40 this 27th day of September, 1906.

EBERHARD FABER.
